UNITED STATES PATENT OFFICE

2,510,195

CUTTER BLADE CAN OPENER

James D. Tinsley, Bakersfield, Calif.

Application December 10, 1946, Serial No. 715,254

2 Claims. (Cl. 30—23)

1

This invention relates to can openers of the type having a prong adapted to hook over the bead on the end of a can to act as a fulcrum to enable a cutter to be forced against the side of the can so as to cut a substantial portion of the can side with a single quick swing of the can opener, and with another quick swing to bend the cut portion of the can end upwardly, so as to expose the contents of the can.

The most common form of can opener that hooks over the bead at the end of the can includes a rotating knife or knives and gears by which the cutting element is operated and as can openers must necessarily be inexpensive, the operating parts are cheaply made and quickly assembled so that the life of can openers of this type is very limited and the operation of can openers of this type is not generally efficient.

With this thought in mind, this invention contemplates a can opener for cutting into the side of the can in which all moving parts are eliminated and in which a single stationary cutting blade is readily forced into and around the can with a single simple action.

In the usual form of can opener, it is also necessary to properly adjust the can opener to the correct position on the can, which not only requires time, but is annoying, and with this though in mind, the can opener of this invention is designed so that with the handle thereof held in the hand, it may be instantly placed upon the can and immediately forced into the can and then turned upward to bend the cut portion of the can outward, the entire operation requiring only a comparatively few seconds.

The purpose of this invention is, therefore, to provide an improved can opener of the type adapted to remove the ends of the can in which all moving parts are eliminated and in which the can may be opened by a novice with very little effort.

Where it is necessary to incorporate moving parts in a can opener, bearings or journals in some form are required, and these require special material, whereas with all moving parts eliminated, as in the can opener of this invention, comparatively inexpensive material may be used, and all machine work and assembling operations are eliminated.

The object of this invention is, therefore, to provide a can opener wherein the holding and cutting elements are formed from a single piece of material so that all rivets, bolts, and the like may be eliminated.

2

Another object of the invention is to provide a can opener, wherein a prong may be placed over the bead of the can, and a knife, fulcrumed by the prong, forced against the side of the can to cut the same.

Another object is to provide a can opener of the type adapted to remove or partially remove the end of the can which not only severs the top from the can, but is provided with a receiving opening into which the severed end of the can passes as it is severed, so that the severed end can be readily bent upwardly or removed from the can.

A further object of the invention is to provide a can opener of the quick-acting type which is of a simple and economical construction.

With these ends in view, the invention embodies a can opener formed of a single sheet of material bent in U-shape with the sides extending to form a handle and in which a projection is formed on the end of one of the sides and a knife blade on the associated edge of the other side, wherein with the projection placed over the bead at the end of the can, the knife blade may readily be forced through the side of the can beneath the end thereof to be severed.

Other features and advantages of the invention will appear from the following description taken in connection with the drawings, wherein:

30 Figure 1 is a plan view of the can opener.
Figure 2 is a side elevation of the can opener showing the same in operative position on a can, the can being shown in dash lines.
Figure 3 is a right hand end elevation of the can opener.

Referring now to the drawings wherein like reference characters indicate corresponding parts, the can opener of this invention is formed from a metal sheet to provide a cutting blade 10 which forms the lower side of the device, one longitudinal edge of the blade 10 being return bent at 11 to joint one longitudinal edge of the upper side 12 which is parallel to the blade 10. At the forward corner of the upper side 12 remote from the bead 11 is a forward projection 13 having a depending L-shaped flange or prong 14, which depends to the level of the top of the blade 10. As shown in Figure 1, the cutting edge 10' of the blade 10 is transversely angulated, so that one end of the blade edge is closely spaced from the flange 14, the latter end of the blade edge being cut off at the corner, as indicated at 28, to define an incising point 27. The point 27 is adapted to be forced into the side of a can 15 with the flange 14 engaged with the inward

side of the bead 15' on the can end. The device is then adapted to be swung sideways, with the flange 14 acting as a fulcrum, so that the cutting edge 10' of the blade 10 will cut the side of the can below the bead 15' for substantially one half of the distance around the can with a single stroke. To remove the entire end of the can, it is only necessary to advance the prong 14 to a new position about half-way around the can and then with a second similar stroke, sever the remaining half of the end of the can. In this action the severed can end will slide into position between the blade 10 and the upper plate 12, and, in the event that the can end is completely severed from the can, the severed end will be located between the sides 10 and 12, so that the can end can be readily removed. In the event that only half of the can end is severed, the severed portion can be readily bent upwardly by raising the device. The blade 10 and upper side 12 have rearward extensions forming a handle 17, and are connected along one edge by the portion 11. The handle may be provided with a notch 18 in one edge having a hook 19 for removing bottle caps, and the rear end of the handle may be provided with a projection 20 forming a screw driver. A corkscrew 21 may be mounted within the handle on a pin 22, and a pick or other device 23 may be similarly mounted on a pin 24. The can opener may also be provided with a laterally extending semi-circular ring 25, having toothed sections 26 therein that may be used for gripping jar tops to facilitate removing the same from a jar. Other elements or devices may be incorporated in the handle or parts of the can opener as may be desired.

The can opener of this invention, however, includes primarily a sheet of material bent in the form of a U with the forward end of one of the arms thereof sharpened to form a knife edge, with a prong extending from the forward end of the other arm positioned to co-act with the knife edge, wherein with the prong hooked over the bead at the end of a can, the knife edge may be forced into the side of the can for cutting the end of the can from the body portion thereof; and with the parts arranged in this manner, the cut portion of the can may readily be bent upwardly or picked up by the can opener so that it will not fall into the can.

What is claimed is:

1. A can cutter comprising a single sheet of metal bent along a longitudinal line to provide

upper and lower parallelly spaced plates connected together along one longitudinal edge, said upper plate having a forward projection on its forward end having a depending fulcrum prong adapted to be engaged behind the bead on the end of a can to be cut, the forward end of said lower plate terminating in a transversely extending cutting edge adapted to be applied to the side of the can below the bead, said cutting edge being transversely angulated whereby rocking said plates toward one side with said fulcrum operatively engaged with the inner side of the can bead causes said cutting edge to cut through the side of the can to produce a cut extending for a substantial portion of the circumference of the can.

2. A can cutter comprising a single sheet of metal bent along a longitudinal line to provide upper and lower parallelly spaced plates connected together along one longitudinal edge, said upper plate having a forward projection on its forward end having a depending fulcrum prong adapted to be engaged behind the bead on the end of a can to be cut, the forward end of said lower plate terminating in a transversely extending cutting edge adapted to be applied to the side of the can below the bead, said cutting edge being transversely angulated whereby rocking said plates toward one side with said fulcrum operatively engaged with the inner side of the can bead causes said cutting edge to cut through the side of the can to produce a cut extending for a substantial portion of the circumference of the can, said forward projection being displaced toward one side of said upper plate and said cutting edge being angulated toward the opposite side of said lower plate, and a forwardly projecting incising point on said cutting edge located adjacent to said projection.
